UNITED STATES PATENT OFFICE.

GEORGE O. DRAPER, OF HOPEDALE, MASSACHUSETTS, ASSIGNOR TO DRAPER COMPANY, OF PORTLAND, MAINE, AND HOPEDALE, MASSACHUSETTS.

YARN-SPINNING APPARATUS.

SPECIFICATION forming part of Letters Patent No. 707,215, dated August 19, 1902.

Application filed October 26, 1900. Serial No. 34,421. (No model.)

To all whom it may concern:

Be it known that I, GEORGE O. DRAPER, a citizen of the United States, and a resident of Hopedale, county of Worcester, and State of 5 Massachusetts, have invented an Improvement in Yarn-Spinning Apparatus, of which the following description, in connection with the accompanying drawings, is a specification, like letters on the drawings representing 10 like parts.

My invention relates to ring-spinning apparatus wherein the ring is rotatably mounted on the ring-rail of the frame, the pull of the yarn on the traveler, which latter is rev- 15 oluble on the ring, finally overcoming the inertia of the ring and causing the ring itself to rotate at very high speed, the ring at such time appearing to the eye to float in the air.

In my present invention I have provided 20 the ring with an overhanging lint-guard, and in order to limit the upward movement of the ring I have provided a plurality of stops, which are extended through radial recesses in the annular ring-seat to engage the ring 25 beneath the lint-guard. The latter thus protects the limiting means, so that there is little or no opportunity for lint to collect thereupon.

Figure 1 is a view in side elevation and 30 section of a portion of a ring-rail with a ring-spinning device embodying one form of my invention applied thereto, the spindle and bobbin being partly shown in dotted lines. Fig. 2 is a top or plan view of the ring seat 35 or support, and Fig. 3 is a side elevation of the ring illustrated in Fig. 1.

I have herein shown only the part of a ring-spinning apparatus which immediately cooperates with my invention—viz., the ring- 40 rail—as any well-known or usual ring-spinning frame and its appurtenances can be used in connection with my invention.

Referring to Fig. 1, the ring-rail R, having the aperture R' for the passage of the spindle S or bobbin B therethrough, has in the 45 present embodiment of my invention an annular ring seat or support a, attached thereto by suitable headed screws s, which pass through holes a' in the bottom of preferably 50 diametrically-located ears a², extended be-

yond the periphery of the seat. The ring itself comprises a top or head b, which is laterally extended at its periphery to present an overhanging projection or flange b', which forms the top of an annular external recess 55 b² in the body or web b³ of the ring, the formation of the recess leaving a projection or rib b⁴ at or near the lower end of the web. This lower projection b⁴ is of less external diameter than the flange b', as is clearly 60 shown in Figs. 1 and 3, and enters the ring-seat, a slight clearance being permitted between them, so that the ring may have a limited radial movement as well as free rotative and axial movement. The flange b' 65 overhangs the ring-seat and rests upon the top thereof when the ring is at rest, as in Fig. 1, the ring having a suitable traveling race b⁵ for a traveler t of any suitable construction, the race herein shown being vertical. The 70 holding-screws s are herein shown as extended through flat plates or stops d of any suitable material—such as fiber, leather-board, &c.—which project into the annular recess b² of the ring beneath the overhanging flange b', 75 the vertical height of the recess being greater than the thickness of the stops, permitting a limited vertical movement of the ring under the stress of the yarn. The projection b⁴ below the stops limits the upward movement of 80 the ring, and it will be manifest that the co-operating parts of the latter and the stops d are protected from lint or dust by the overhanging flange b', which thus constitutes a 85 lint-guard.

By the construction shown the top of the ring offers nothing to catch or collect lint or dust, and owing to the hidden or concealed location of the operating portions of the stops access of lint thereto is practically prevented. 90 The stops are shown as resting upon cushions or pads d⁵, of felt, rubber, or other preferably-yielding material to prevent shock, the cushions being held in the ears a² of the ring-seat, said ears being preferably made box-like 95 or socketed to hold the cushions, the latter having a radial recess a⁵ therein opposite each ear to permit the passage therethrough of the stop d and below the annular top face of the seat.

Having fully described my invention, what I claim as new, and desire to secure by Letters Patent, is—

1. An annular seat having a plurality of radial recesses therein, a rotatable ring capable of axial and radial movement relatively to said seat, an overhanging lint-guard on the ring, and a stop extended through each recess in the seat to engage the ring beneath the guard and limit upward movement of the ring.
2. An annular seat having attaching ears on the exterior thereof, and a radial recess through the seat opposite each ear, a rotata-

ble ring axially movable relatively to the seat, 15 and having an external annular groove, a limiting-stop secured to each ear of the seat and extended through the annular recess of the ring, and a lint-guard on the latter overhanging the ring-recess.

20

In testimony whereof I have signed my name to this specification in the presence of two subscribing witnesses.

GEORGE O. DRAPER.
